WRIST SPLINT

Walter J. Jones, La Crosse, Wis.

Application April 25, 1938, Serial No. 204,077

1 Claim. (CL 128—89)

This invention relates to wrist splints such as are used in surgery and it has for an object to provide a wrist splint that is quickly and easily applied and readily removed; that supports the 5 wrist joint and leaves the fingers free for movement, and that deflects the palm of the hand to extend the fingers forward in a natural position. Another object of the invention is to provide a wrist splint which does not interfere with X-raying the wrist when the splint is in position.

Other objects of the invention will be more readily understood from the following specification and from the accompanying drawing forming part thereof, in which:

15 Figure 1 is a back view of the forearm and hand with the wrist splint in place;

Figure 2 is a front view of the forearm and hand with the wrist splint in place;

Figure 3 is a side view, corresponding to Figures 1 and 2; and

Figure 4 is a section on line 4—4, of Figure 2.

This invention is a splint for rigidly securing an injured wrist joint where the ulna and radius bones unite with the bones of the hand, and comprises a sleeve or socket which is laced around the forearm and which is open at the lower end to embrace the palm of the hand. It is held in place by a strap for uniting the open side of the socket and which passes under the thumb and is secured 30 by a buckle at the back.

The device is made rigid by a rigid reinforcing member extending longitudinally of the socket and having its lower end curved to correspond with the palm of the hand. A pocket is provided 35 in the socket for securing this member in place.

An important feature of the invention is that it can be quickly applied to an injured limb and the limb may be X-rayed without removing the splint. The socket is preferably made of leather and the splint may be made of sheet aluminum 40 which is substantially transparent to X-rays, or it may be made of stiff vulcanized fiber.

In the drawing, the numeral 11 is the socket which is laced at 12 around the forearm, a flap 13

being provided as a protection under the lacing where the members of the socket are brought together. The lower end of the socket is contracted as indicated at 14 and 15 to embrace the palm of the hand, and the strap 16 is taken from the front side 15 under the thumb and secured by the buckle 18 at the back as indicated in Figure 3.

This enables the lower end of the splint to firmly grip the palm of the hand below the wrist joint 10 where the lacing secures the socket to the forearm and the strap 16 holds the splint in position.

A pocket is provided at 21 extending for the length of the socket. In this pocket, rigid member 23 is located, of aluminum, fiber or other suitable material, and this member is curved at 22 to conform to the palm of the hand and to force the palm of the hand backwards relative to the socket so that the fingers normally rest in the forward or cock up position, indicated in Figure 3. 15 20

In this construction the wrist joint is securely held against movement while the fingers are free, whereby the user is able to use his hand for light work and freely exercise his fingers.

The lacing and the strap attachment are adjustable so that swellings can be compensated for and the device can, within a limited range, be applied to different sizes of hands. 25

What is claimed is:

A wrist splint comprising a sleeve adapted to 30 be laced on the forearm and having the lower end embracing the palm of the hand and having an opening for the fingers and an opening for the thumb, a palm strap adapted to be passed between the thumb and the forefinger for adjusting the 35 tension of said splint about the palm independently of the laced portion, and a rigid plate secured to said sleeve, said plate being curved to conform to the curve of the palm of the hand, wrist and lower portion of the forearm, whereby 40 the palm of the hand may be held back from the longitudinal line of the socket and in rigid relationship to the wrist and forearm.
